UNITED STATES PATENT OFFICE.

GUSTAV EGLOFF, OF CHICAGO, ILLINOIS, ASSIGNOR TO UNIVERSAL OIL PRODUCTS COMPANY, OF CHICAGO, ILLINOIS, A CORPORATION OF SOUTH DAKOTA.

APPARATUS FOR CRACKING OIL.

Application filed January 3, 1921, Serial No. 434,457. Renewed March 25, 1927.

This invention relates to improvements in apparatus for cracking oil and refers more particularly to an apparatus for conserving heat units and securing the maximum amount of pressure distillate from the original charge.

It is well understood in the art of cracking oil that the generated vapors contain a large percentage of incompletely cracked condensates which have to be subjected to reflux condensing action and subjected to further cracking. Otherwise, the Baumé gravity of the pressure distillate would be much too low and the operation would be inefficient. Under present practice, there is a very large heat loss due to the necessity of frequently condensing these heavier vapors and again reheating them.

In the present invention, all of the reflux condensation takes place in the body of the still itself, this reflux condensation being produced by the cool incoming oil, which oil is also preheated by the generated vapors, before it enters the main body of oil in the still. The economy of my process will be apparent to anyone skilled in the art of cracking oil. At the same time, I have a very simple method of operation, and apparatus devoid of complicated mechanism.

In the drawings:

Fig. 1 is a view, partly in side elevation, and partly in vertical section, of my improved apparatus.

Fig. 2 is a section taken on line 2—2 of Fig. 1.

Referring particularly to the drawing, 1 designates the furnace, having burner 2, bridge wall 3 and usual stack (not shown). In the furnace is mounted the still 4, which in the present instance, takes the form of a horizontal or shell type. The still 4 is provided with the pressure gauge 5, liquid draw-off line 6, controlled by throttle valve 7. Suitably arranged in the still is an open ended pipe 8, concentrically supported in but spaced away from a slightly larger pipe 9. The pipe 9 is closed at both ends as shown at 10 and 11. It in fact forms a jacket for the open ended pipe. The raw charging stock is introduced to the system by means of feed pump 12, connected to any suitable source of supply, and feed pipe 13 having throttle valve 14 and connected as shown at 15 to the closed end 10 of the pipe 9. To the end 11 of the pipe 9 is connected

a downwardly extending pipe 16, which at its lower end connects to a perforated pipe 17 extending longitudinally along the lower part of the still. The vapor space of the still is provided with vapor outlet pipe 18 having throttle valve 19, which pipe 18 leads to condenser coil 20 seated in condenser box 21. The coil 20 connects to the upper end of receiver 22, which receiver has pressure gauge 23, liquid level gauge 24, gas outlet pipe 25 controlled by throttle valve 26 and liquid drawoff pipe 27 controlled by throttle valve 28.

The process is operated as follows: The raw oil, as for example, a Kentucky gas oil, of 34 degrees Baumé gravity, is continuously fed by the feed line 13 into the narrow chamber 29 formed by the concentric pipes 8 and 9. The oil passes out through the pipe 16 and thence through the perforations 30 in the horizontal pipe 17. The oil may be heated to a temperature of say, 725 degrees F., and subjected to a pressure of say, 140 pounds. As the generated vapors rise, they will be cooled by the incoming raw oil and the heavier portions thereof will be condensed and fall back into the liquid body of oil in the still for further treatment. The lighter vapors namely, those which are sufficiently cracked, as for example, the gasoline-like constituents, will pass out to the condenser where they are condensed and delivered to the receiver. The reflux condensation produced by the incoming stream of cold oil also serves to preheat the incoming raw oil so that it more nearly approaches the desired temperature. The result is an extremely efficient operation from the standpoint of economy, and it may be here noted that this question of fuel economy is at present of great importance and is constantly increasing in importance.

It is to be noted that the pipes 8 and 9 are located in the vapor space of the still and the dimensions of these pipes and the thickness of the oil in the enclosing jacket may be regulated so as to produce the desired cooling effect and no more.

I claim as my invention:

1. In an apparatus for cracking oil, the combination with a still adapted to receive a bulk supply of oil, a reflux apparatus in said still comprising an annular conduit of restricted cross sectional area for the passage of raw oil therethrough, means for supply-

ing raw oil to said conduit, and means for discharging the oil from the conduit into the oil in said still at points adjacent the bottom thereof.

2. An apparatus for cracking hydrocarbon oil comprising an enlarged chamber in which a bulk supply of oil is adapted to be maintained and wherein vaporization occurs, a reflux apparatus located in the vapor space of said enlarged chamber, said reflux apparatus comprising an elongated annular conduit of restricted cross sectional area, means for passing cool oil through said reflux apparatus to cool the vapors evolved from the oil in said chamber and effect a reflux condensation thereof, means for delivering oil which has passed through said reflux apparatus into the body of oil in said en-

larged chamber and means for removing unvaporized oil from said enlarged chamber. 20

3. An apparatus for cracking hydrocarbon oil comprising a still, means for maintaining a body of oil in said still under cracking conditions of temperature and pressure, means for passing an annular stream of charging oil being supplied to the apparatus through the vapor space in said still and means for thereafter uniting the charging oil which has passed in an annular stream through the vapor space of the still with the body of oil maintained in the still, means for taking off uncondensed vapors from the still and means for subjecting such vapors to final condensation. 25 30

GUSTAV EGLOFF.
